[57] CLAIM

The ornamental design for a hoist gear lubricator, as shown and described.

DESCRIPTION

FIG. 1 is a front elevational view of a hoist gear lubricator showing my new design, the rear view being unadorned and therefore not shown;

FIG. 2 is a top plan view thereof;

FIG. 3 is a bottom plan view thereof;

FIG. 4 is a right side elevational view thereof; and,
FIG. 5 is a left side elevational view thereof.

The broken line showing of a motor, pulleys, belt, worm gear and toothed wheel gear is for illustrative purposes only, showing the environment of the invention, and forms no part of the claimed design.
